UNITED STATES PATENT OFFICE.

WARREN WOOD, OF PATERSON, NEW JERSEY.

ROCK-DRILL.

997,591.

Specification of Letters Patent. Patented July 11, 1911.

Application filed January 20, 1911. Serial No. 603,711.

To all whom it may concern:

Be it known that I, WARREN Wood, a citizen of the United States, residing at Paterson, in the county of Passaic and State of New Jersey, have invented a certain new and useful Improvement in Rock-Drills, of which the following is a specification.

The invention relates to the construction of the lower cylinder-head or "front head", and the object of the invention is to provide a head and packing-sleeve therefor so constructed as to permit the sleeve to be removed easily and a new one substituted when required, with means for holding the sleeve reliably in place and for cushioning the effect of the piston blows.

Another important object is to provide means operating in conjunction with the cushioning means for locking the nuts of the holding-bolts and preventing the slackening or loosening of such nuts under the heavy jars and vibrations due to the reciprocations of the piston and its connected parts.

The invention consists in certain novel features of arrangement and details of construction by which the above objects are attained, to be hereinafter described and pointed out in the claims.

The accompanying drawings show the invention as it has been carried out in practice in a head designed for service on an air-operated drill.

Figure 1 is a front elevation of the head and a portion of the drill-cylinder and connected parts. Fig. 2 is a corresponding plan or end view seen from below, with the drill-bearing portion of the piston shown in transverse section. Fig. 3 is an elevation showing the interior face of one of the two halves or portions constituting the body of the head. Fig. 4 is a vertical section through the head, taken on the line 4-4 in Fig. 2. Fig. 5 is a corresponding section taken on a plane at a right angle to that of Fig. 4. Fig. 6 is a view of the under face or flange of the packing-sleeve. The remaining figures are on a larger scale and show the locking means for the sleeve holding bolts. Fig. 7 is a plan view of the upper face of the locking-washer. Fig. 8 is a corresponding edge view. Fig. 9 is a plan showing the under face of the same washer.

Fig. 10 is a view of the bearing face of one of the nuts. Fig. 11 is a corresponding elevation.

Similar letters of reference indicate the same parts in all the figures.

A is a portion of the lower end of the cylinder, and A¹ is the front head made in two portions or halves each the counterpart of the other and held together by bolts A². The head thus joined is secured to the cylinder by side-rods as usual and is bored and counterbored to receive the piston-rod B, 65 packing-sleeve D and packing C. The packing-sleeve has a flange D¹ in which are oppositely located openings d, and is split longitudinally, the line of division passing through the openings d, to permit its application around the piston rod and introduction within the head. On opposite sides of each portion of the head is a swell or lug A³ each recessed to produce when applied together a rectangular cavity a adapted to receive the rectangular head E¹ of a bolt E, and having each a smaller recess a¹ matching to the body of the bolt and forming with the cavity a shoulders A⁴ adapted to support the heads E¹ and resist downward strains 80 on the bolts. The latter extend through the openings d in the flange D¹ and receive nuts E². Between the flange D¹ and under face of the head A¹ is a gasket F of rubber or suitable elastic or yielding material, serving 85 as a cushion to absorb shocks of impact upon the head and soften the transference of such shocks to the flange D¹ and its holding-bolts E E¹ E².

In order to insure the nuts E² against 90 loosening, the inner face of each is provided with a series of radial grooves e receiving corresponding rounded ridges G¹ on a washer G. The latter is held against rotation by pins or projections G² on the opposite face, 95 received in corresponding pin-recesses or notches d¹ formed in the abutting edges of the flange D¹ adjacent to each bolt-opening d, as illustrated in Figs. 5 and 6.

In applying the sleeve the two sections 100 are placed together encircling the piston rod, and the gasket F, which is cut radially at one point to permit its application, is placed upon the upper face of the flange D¹ and the tubular sleeve portion inserted within the 105 head, in which the bolts E have been pre-

viously positioned, with the lower ends of the bolts extended through the openings d and similarly located openings in the gasket. The washers are then passed over the bolt-ends and the pins G^2 engaged in the notches or pin-recesses d^1 in the under face of the flange D^1 . The nuts E^2 are then applied and screwed up against the washers which yields sufficiently by compressing the gasket

10 F between the flange D^1 and lower face of the head, to permit the lands or plane spaces between the grooves e on the nuts to ride over the ridges G^2 on the washers until a degree of compression is attained at which

15 further travel of the nuts is strongly resisted. At this point the nuts are turned enough farther to arrive at one of the positions in which the grooves and ridges coincide. Thus locked the nuts are held reliably

20 against backing off and the sleeve is strongly but yieldingly joined to the head.

Cotterpins H inserted through holes a^2 a^2 drilled through the lugs A^3 from side to side, serve to maintain the bolts in position while

25 the parts are being assembled and also as auxiliary means to the frictional grip of the bolts in the recesses a a in preventing the displacement of the bolt-heads. The abutting edge of one of the sleeve sections is

30 notched as in Fig. 4 to receive a correspondingly shaped swell on the other, thus insuring the proper relation of the halves.

The failure of a front head as commonly constructed is usually due to internal wear.

35 By the employment of the sleeve such wear is received by the latter, and by a reversal of the above operation the sleeve when worn may be easily removed and a new one substituted, thus increasing the life of the head

40 indefinitely. The improved construction also permits the easy removal of old and the introduction of new packing rings C as required, and allows the sleeve to be made of material different from that of the head and

45 better adapted to resist wear.

Although the invention is shown and described as applied to an "air-head" it will be understood that it will serve successfully with the packing-sleeve or gland and packing of a "steam-head."

By forming the recesses a a on the exterior of the head and partly in both portions thereof, they are easily accessible to the tools of the machinist, and any surplus metal

55 in the angles, due to imperfect casting, may be easily reached and removed or other imperfections corrected in any parts of the recesses.

I claim:

60 1. In a rock-drill, a cylinder-head divided axially into two portions, a packing-sleeve having a flange and received in said cylinder-head, holding-bolts securing said sleeve to said cylinder-head, the latter having cavities in its exterior receiving the

heads of said holding-bolts, and formed by recessing adjacent parts of both of said cylinder-head portions, the body portions of said bolts lying in recesses opening into said cavities and formed partially in both of said cylinder-head portions, said bolts extending axially of said cylinder-head through said flange, and receiving nuts on their outer ends.

2. A cylinder-head, a packing-sleeve having a flange, elastic material between said sleeve and cylinder-head, bolts received in said cylinder-head and extending through said flange, pin-recesses in the latter adjacent to said bolts, a washer for each of said bolts, pins on one face of said washer engaged in said pin-recesses, radial ridges on the other face of said washer, and a nut for each of said bolts having grooves in its bearing face matching to the ridges on said washer.

3. A cylinder-head, a packing-sleeve having a flange and divided axially into two portions, said flange having bolt-openings and pin-recesses formed partly in each of such portions, an elastic gasket between said flange and cylinder-head, holding-bolts secured to said cylinder-head and extending through said bolt-openings and gasket, a washer for each of said bolts, pins on one face of said washer engaged in said pin-recesses, radial ridges on the other face of said washer, and a nut for each of said bolts, having grooves in its bearing face matching to the ridges on said washer.

4. In a rock-drill, a cylinder-head divided axially into two portions, a packing-sleeve and flange thereon divided axially into two portions, said flange having bolt-openings and pin-recesses formed partly in each of said flange portions, an elastic gasket between said flange and cylinder-head, holding-bolts securing said sleeve to said cylinder-head and extending through said gasket and bolt-openings, said cylinder-head having cavities in its exterior receiving the heads of said bolts and formed by recessing adjacent parts of both of said cylinder-head portions, the body portions of said bolts lying in recesses opening into said cavities and formed partially in both of said cylinder-head portions, a washer for each of said bolts, pins on one face of said washer engaged in said pin-recesses, radial ridges on the other face of said washer, and a nut for each of said bolts having grooves in its bearing face matching to the ridges on said washer.

5. A cylinder head formed in sections, each section having a lug with the lugs recessed upon their adjacent faces forming a cavity to receive the head of a securing bolt, said recesses being accessible from the exterior of the head.

6. A cylinder head formed in sections,

each section having a lug with the lugs recessed upon their adjacent faces forming a cavity to receive the head of a securing bolt, said recesses being accessible from the exterior of the head, said recesses having shoulders to support the head of the bolt and resist downward strain thereon.

In testimony that I claim the invention above set forth I affix my signature, in presence of two witnesses.

WARREN WOOD.
